UNITED STATES PATENT OFFICE.

DAVID S. ESTEN, OF HINSDALE, MASSACHUSETTS.

IMPROVEMENT IN DEVICES FOR STOPPING THE SHUTTLE IN POWER-LOOMS.

Specification forming part of Letters Patent No. 39,803, dated September 8, 1863.

To all whom it may concern:

Be it known that I, DAVID S. ESTEN, of Hinsdale, in the county of Berkshire and State of Massachusetts, have invented a new and useful Improvement for Stopping the Shuttle in Power-Looms; and I do hereby declare that the following is a full, clear, and exact description of the same, reference being had to the accompanying drawings, forming part of this specification, in which—

Figure 1 is a vertical section of a portion of the lay and shuttle-motion and of my improvement, parallel with the raceway, illustrating the application of my invention to the picker-staff. Fig. 2 is a vertical section of the same at right angles to Fig. 1. Fig. 3 is a bottom view of that portion which constitutes the principal feature of my invention.

Similar letters of reference indicate corresponding parts in the several figures.

This invention consists in an improved mode of applying a spring to operate upon the picker-staff for the purpose of checking or stopping the shuttle in the shuttle-box, whereby I am enabled to use a lighter binder-spring and to obviate the necessity of producing so much friction upon the shuttle as it enters the box.

To enable others skilled in the art to make and use my invention, I will proceed to describe its construction and operation.

A is the race-board of the lay; B, one of the swords, and C the shuttle-box.

D is the pricker-staff, which may be operated in the usual manner to throw the shuttle.

E and F are the two cylinders with toothed edges, fitting together like the two portions of a rag-wheel clutch. The cylinder E is made in the same piece with plate E', which is secured to the front part of the bottom of the shuttle-box and is stationary. The cylinder F, is fitted to turn on a pin, a, which is firmly secured in the cylinder E, and which is concentric with both cylinders, and upon this pin there is coiled outside of the cylinder F between the said cylinder and a stop, d, on the end of the pin a spiral spring, b, which presses the said cylinder F toward the cylinder E, and so tends to prevent the cylinder F from turning in the only direction in which

it is permitted to turn from its normal position by its wedge-like teeth c c, on the two cylinders—viz., in the direction of the arrow shown in Fig. 1. The stop d may consist of a nut and be fitted to a screw-thread on the pin a for the purpose of adjusting the pressure of the spring.

e is a strap, of leather or other material, which is wound partly around the cylinder F, and one end of which is secured to the said cylinder by a hook, f, and the other end secured to a hooked rod, g, which is permitted to slide horizontally in guides h h, secured to the bottom of the lay near the end thereof. The hook of this rod is wide enough and is so situated as to allow the picker-staff to play freely within it to throw the shuttle.

The operation of the check is as follows: When the shuttle passes into the box, it strikes the picker-staff and drives it back, and the staff, coming into contact with the bend of the hook of the rod g, presses back the said hook with it toward the end of the lay, and in so doing unwinds the strap from the cylinder F and turns the said cylinder in the direction of the arrow shown in Fig. 1. By this action of the cylinder F the inclined surfaces of its wedge-like teeth, acting against the corresponding surfaces of the teeth on the cylinder E, force it back from the latter cylinder and produce the compression of the spring b, and the resistance offered to the turning of the cylinder F increases with the compression of the spring till it becomes sufficient to stop the said cylinder, and so causes the hook to arrest the picker-staff and the shuttle. The spring then gradually reacts upon the cylinder F and causes it to turn back in the opposite direction to the arrow till it is stopped by the teeth on the cylinder E, and the strap e is thus wound up again and caused to draw the picker-staff toward the center of the loom as far as permitted by the guides h h, which serve as stops to the hook g, and this is done so gradually as not to throw the shuttle away from the staff, in contact with which it remains till the staff is operated by the picker-motion to throw it across the loom.

The invention is to be applied at each side

of the loom, but I have thought it sufficient for its illustration to show its application to one side.

What I claim as my invention, and desire to secure by Letters Patent, is—

The spring *b*, applied to act upon the picker-staff through the medium of the two toothed cylinders *E* *F*, strap *e*, and hooked rod *g*, the

whole applied and arranged to operate substantially as and for the purpose herein specified.

DAVID S. ESTEN.
